Harold J. Sushan, Burbank, Calif.

Application February 16, 1952, Serial No. 18,551

Term of patent 7 years

(Cl. D4—3)

To all whom it may concern:

Be it known that I, Harold J. Sushan, a citizen of the United States, residing at 419 North Lomita Street, Burbank, State of California, have invented a new, original, and ornamental Design for Collapsible Container Tube Dispenser and Hanger, of which the following is a specification, reference being had to the accompanying drawing, forming a part hereof.

Fig. 1 is a front elevational view of a collapsible container tube dispenser and hanger embodying my new design;

Fig. 2 is a top plan view thereof; and

Fig. 3 is a vertical sectional view taken substantially along the line 3—3 of Fig. 1.

I claim:

The ornamental design for a collapsible container tube dispenser and hanger, as shown.

HAROLD J. SUSHAN.
